UNITED STATES PATENT OFFICE.

JOHN M. GILMAN, OF LANSING, KANSAS.

WASHING-MACHINE.

SPECIFICATION forming part of Letters Patent No. 357,479, dated February 8, 1887.

Application filed February 5, 1886. Serial No. 190,911. (No model.)

To all whom it may concern:

Be it known that I, JOHN M. GILMAN, a citizen of the United States, residing at Lansing, in the county of Leavenworth and State of 5 Kansas, have invented certain new and useful Improvements in Washing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The main objections to all that class of washing-machines commonly known as "agitators" with which I am familiar is the formation of dead or still water—in the circular-tub machines the water is dead or still in the center, while in square, octagonal, and other 25 water-receptacles, in which there are corners, the water is dead or still in said corners as well as in the center of the receptacle—and their inability to wholly cleanse small articles of wearing-apparel—such as wristbands or cuffs, 25 collars, and the like—which are usually more soiled than larger articles, in the same space of time as that occupied in cleansing the larger articles.

Now, my invention has for its object to provide a machine in which every particle of water in the tub will be thoroughly agitated and set in motion, and by which the smaller articles of wearing-apparel above named will be thoroughly cleansed in the same time as the 35 larger less soiled articles, and which will be simple of construction and easy of operation; and it consists of the parts and combinations of parts, hereinafter described and claimed.

In the accompanying drawings, forming a 40 part of this specification, Figure 1 is a side elevation of my improved machine; Fig. 2, an enlarged perspective view of the agitators and attachments; Fig. 3, a detail view, and Fig. 4 a sectional view.

45 A represents the frame for supporting the tub or suds-receptacle B. This frame A consists of four uprights, connected near their lower ends by cross-bars, on which rests a platform, C, for the tub B, and top D, having a 50 square or other suitably-shaped opening through which the articles to be washed are

placed in the tub. The top D is secured, by means of screws or other easily-removable fastenings, to the uprights and rests on the tub B, so as to secure the same in position and at 55 the same time permit of ready access thereto, should it become necessary to withdraw it. A platform, a, projects from one of the bottom timbers on one side of the frame. To this platform I firmly secure an upright, b, and 60 brace it in position by means of the rods c, secured to the platform and upright. A guard-plate, d, is secured at each end to the upright b, between which and said upright a large spur-wheel, e, and a small spur-wheel, f, are 65 journaled and mesh together. The shaft of the wheel e carries a crank, g, by which it may be rotated, and the shaft of wheel f carries a crank, h, to the outer end of which one end of a rod, k, is pivoted, the other end being pivoted 70 to the arm E of a segmental beveled gear-wheel, F, which is pivoted to a short stud, G, projecting from the cover H, and meshes with a cone or beveled gear wheel, F', on the end of a bolt, hereinafter described. This cover is 75 provided with an offset, I, which fits down closely in the opening in top D, referred to above, so as to completely cover the tub B. To the under side of the cover H, at its center, is hung a plate, K, by means of a screw- 80 bolt and nut, m, the upper end of this bolt projecting through the cover and carrying the cone-gear F'. The plate K has cast with it four knobs or projections, n, one on each corner, through each of which a hole is drilled in 85 a longitudinal direction. To these knobs are hung the agitators L. These agitators, the plate K, and all other metallic parts which are within the tub or in direct contact with the suds are preferably of galvanized iron, as it 90 is not disposed to rust and thereby injure the clothes.

The agitators L are oblong in shape, their widest or butt ends being upward to conform to the shape of the tub B, which is flaring 95 from its bottom upward, and in their butt-ends a recess is formed, so that they may be fitted over the knobs n and there hinged by a bolt passing through them and the knobs.

To regulate the distance apart of the lower 100 ends of the agitators, and thus adjust the machine to the strength of the person operating

it, and also for the purpose of securing the much-soiled small articles to be washed, I provide the four wires M, (clearly shown in Fig. 3,) the screw-bolt N, clamping disk or washers O O', ring P, and thumb-nut R. The washer O is first placed upon the bolt N, then the ring P, and then the washer O' and nut R. One end of each wire M is then secured in any suitable manner to the lower or pointed end 10 of each of the agitators and the other end passed through the ring P and outward, so that it will bear on both of the washers or clamping-disks O O'. It will thus be seen that the distance apart of the lower ends of the agitators may be regulated with great nicety and firmly held in their adjusted position by merely turning the thumb-nut R until it causes the disk O' to clamp the wires securely between it, the disk O, and the ring P, the latter also 20 preventing them escaping to either side or away from the disks O O'. The wires also prevent the formation of still water in the center of the tub, while the gradually-increasing diameter of the tub and agitators creates a current 25 or "boiling" of the suds which is not attained by any circular machine of equal diameter at all points between its bottom and top. The clothes to be washed are first placed in the tub B, with suitable quantities of soap and 30 water, the articles to which it is desired to give extra washing being placed within the space between the agitators. The crank g is then turned, which rotates the wheel e. The latter, meshing with wheel f, rotates it, and 35 through crank-arm h and rod k gives an oscillating motion to the segment-gear F, which, meshing with cone-gear F', rapidly oscillates the plate K and the agitators in a steady uniform manner.

40 Having thus described my invention, what I claim as new, and desire to secure by Letters Patent, is—

1. In a washing-machine, the combination of the oscillatory plate K, the hinged agitators L, and wires M, for regulating the distance

5 apart of the lower ends of said agitators, substantially as and for the purpose described.

2. In a washing-machine, the combination of the plate K, the hinged agitators L, the wires M, and means for securing the free ends 50 of said wires, substantially as and for the purpose described.

3. In a washing-machine, the combination of the plate K, the agitators L, the wires M, the bolt N, the clamping-disks O O', the ring P, 55 and thumb-nut R, substantially as and for the purpose described.

4. In a washing-machine, the combination of the flaring tub B, the cover H, having offset I, the plate K, having the perforated knobs n, the bolt and nut m, the agitators L, the wires M, the bolt N, clamping-disks O O', the ring P, and thumb-nut R, substantially as and for the purpose described. 60

5. The combination, in a washing-machine, 65 of the tub B, the cover H, the bolt and nut m, plate K, agitators L, wires M, the bolt N, clamping-disks O O', ring P, nut R, and means for oscillating the plate K, substantially as and for the purpose described. 7c

6. The herein-described washing-machine, comprising a flaring tub, B, a cover, H, a plate, K, pivoted agitators L, the wires M, the screw-bolt N, clamping disks or washers O O', the ring P, thumb-nut R, the cone-gear F', 75 segmental gear F, arm E connecting-rod k, upright b, crank-arm h, guard-plate d, gear or spur wheels e f, and crank g, all as and for the purpose specified.

7. The combination, in a washing-machine, 80 of the plate K, agitators L, wires M, screw-bolt N, clamping-disks O O', and means for holding the wires between the clamping-disks, substantially as described.

In testimony whereof I affix my signature in 85 presence of two witnesses.

JOHN M. GILMAN.
